UNITED STATES PATENT OFFICE

ELMER T. WUEST, OF CINCINNATI, OHIO

COTTON-PREPARED MACHINE

Application filed May 19, 1927. Serial No. 192,759.

This invention relates to a device for use in the manufacture of felt, batting and the like and has for its principal object the provision of a simplified structure wherein one device accomplishes the operations heretofore requiring several machines.

Another object is to provide a device of this kind wherein fewer parts than were formerly used are arranged in a novel manner to the end that the desired results are attained in a different manner.

Another object is to provide a mechanism which is compact in structure, and which operates with greater efficiency than heretofore known devices both in production and in the quality of the product.

Such inventions as are disclosed herein and are not claimed herein form part of divisional application Serial 430,220, filed February 21, 1930.

These and other objects are attained by the means described herein and disclosed in the accompanying drawings, in which:

Fig. 1 is a side elevational view of a device showing the invention, part being broken away and part being shown in dotted lines.

Fig. 2 is a fragmental side view of the device, some of the parts being represented diagrammatically.

Fig. 3 is a view similar to Fig. 2 but showing a possible modification of the device of the invention.

Fig. 4 is a view taken on line 4—4 of Fig. 1.

Fig. 5 is a fragmental detail of part of the device in one position.

Fig. 6 is a view of the same part in another position.

In the manufacture of batting or soft felt from cotton and other fibrous materials there is commonly used a preparer for separating or loosening the larger masses of the fibers. A feeder device then receives the loosened fibers from the preparer and delivers regulated quantities to the so called Garnett machines which arrange the fibers in sheet like form after which such sheets are folded by other mechanism to provide a layer of cotton batting.

In the device of the present invention the preparer, feeder and Garnett machines are replaced with a simpler combination of elements which performs the same work in a better manner and in less time than is possible with the other machines.

By reference to Fig. 1 it will be noted that a suitable base 10 supports a casing 11 which comprises side walls 12, a front wall 13 and a rear wall 14 which is suitably formed to extend about certain of the rolls of the device. The casing 11, which may be open at its top, has a vertical transverse partition 15 extending between walls 12 and an inclined baffle or flange 16 extending from front wall 13 thereby forming a hopper chamber 17 within the casing. As will be noted in Fig. 2 a pair of rolls 18 and 19 close the space between the ends of partition 15 and baffle 16 so that cotton from the bale will remain in hopper chamber 17 so that it may be separated by the rolls 18 and 19. Roll 19 may be termed a picker roll and roll 18 may be termed an agitator roll. The rolls 18 and 19 are provided with rows of sharp spurs indicated diagrammatically by the reference numeral 20. The rolls 18 and 19 are arranged for rotation in the same direction and the points of spurs or teeth 20 extend in the opposite directions, so that the adjacent sides of said rolls, move relatively in opposite directions.

The pointed ends of roll 19 move forwardly into the mass of cotton in the hopper, while the cotton mass slides off the pointed ends of the threads on roll 18. In other words, the teeth on said rolls function in relatively reverse manner, in one case the points are foremost and in the other case the points are rearmost as they are carried through the fiber mass. This relation of the teeth on the rolls prevents the drawing of large masses of the cotton from the hopper into the rolls so that the roll 19 may efficiently separate the fibers from the mass and deliver them in film-like stream to main cylinder 21 which rotates in the same direction as the rolls 18 and 19. A roll 22 operates adjacent the circumference of roll 21 but in a direction opposite thereto, so that adjacent teeth 20 on

this roll and the cylinder move in the same direction. A roll 23 which is also provided with teeth 20 co-operates with cylinder 21 and roll 22 for directing the fibers in sheet like arrangement between the cylinder and discharge roll 24. Discharge roll 24 rotates in a direction opposite to the direction of rotation of cylinder 21 so that the fiber is carried between the lower periphery of the discharge roll and curved bottom 25 of casing 10. A rake or comb 26, provided with a plurality of teeth 27, is mounted for rapid reciprocation adjacent the periphery of discharge roll 24 exteriorly of the casing. The means for vibrating the rake 26 may comprise a shaft 28 upon which are pivotally mounted a plurality of arms 29 which carry the rake 26 at their free ends. A suitable cam 30 may be provided with a pin 31 which 15 extends through a slot 32 in arm 29, rapid rotation of the cam 30 serving to effect rapid reciprocation of the rake 26. The reciprocating rake 26 serves to separate the fiber from discharge roll 24 and to permit it to 20 drop upon a suitable conveyor belt 33.

It will be understood that the device is power actuated and that the direction of rotation of the several rolls and the cylinder may be effected through a suitable gear train indicated generally by the reference character 34. The roll 19 is slightly greater in diameter than roll 18 and therefore has somewhat greater surface speed when the rolls are rotated at substantially uniform speed. This arrangement of rolls makes possible a more thorough separation of the fibers than was heretofore possible with the Garnett machine and preparer. The rates of speed of the rolls are substantially as follows: Roll 19 approximately 975 R.P.M.; roll 18 approximately 1175 R.P.M.; roll or cylinder 21 approximately 270 R.P.M.

In Fig. 3 there is shown a possible modified and simplified form of device wherein a roll such as 19, provided with the customary teeth 20 is used in conjunction with a smooth roll 35. This very simple mechanism is effective for thoroughly dividing masses of cotton direct from the bale so that it may be handled by pneumatic means for filling upholstery casings and the like.

From the foregoing it will be noted that the device of this invention occupies a minimum of floor space and that it eliminates the preparer and feeder heretofore used in conjunction with Garnett machines. It will be further noted that the device of the invention performs its work with a lesser number of parts than are found in the Garnett machine and at the same time accomplishes the operations of the entire group of machines with greater efficiency and with greater speed. The increased efficiency is believed to be due to the fact that the action of rolls serves to keep the mass of cotton M in a state

of agitation which in effect is equivalent to suspending said mass in contact with the rolls while the fibers are being separated therefrom.

In the operative device produced and embodying the invention disclosed herein, it was found that a six (6) to (5) speed ratio of the rolls 19 and 18 disposed one above the other with aligned diameters of the rolls at about 60 degrees to the horizontal, gave excellent results in volume and character of product. Roll 19 is rotated preferably at 975 revolutions per minute and roll 18 at 1175 revolutions per minute. In that device the teeth on the rolls extended about the respective rolls in opposite directions. Such teeth on commercial rolls are spiral. The spirals on the rolls used tend to move the cotton mass in opposite directions.

The rolls 18, 19, impart motion to the mass of material in the direction of the arrows shown above said rolls on the hopper in Fig. 1, for rotating the mass of material in the hopper above said rolls. The mass of material preferably has substantially unconfined rotary movements in said hopper, being urged toward the rolls by gravity, in the exemplification stated. The surface movements of the rolls, urge similar movement upon the mass, which is also deflected away from the roll 18 by the transverse vertical partition 15, the mass continuing in its movement, and the moving surface of the mass being again directed toward the rolls by the front wall 13 and the inclined baffle 16.

The teeth or spurs on the agitator and picker rolls apparently cooperate in the following manner. It is believed that a buoyant action results from the rotation of the mass in the hopper 11, that the agitator roll not only assists the picker roll in revolving the mass but also partly extricates individual fibers from the mass, thereby making it possible for the teeth on the picker roll to subsequently withdraw such loosely held fibers and to deliver the released fibers in a web to the cylinder 21, that functions primarily as a conveyor, or at most as a supplemental carding element. It is believed that fibers, held tightly by the mass cannot be removed by the picker roll alone, because the rotating mass tends to carry along any tightly held fibers, rather than that the engagement of fibers securely held to the mass and engaged by the teeth on the picker roll would check the movement of the mass to permit succeeding teeth on the picker roll to engage such securely held fibers to assist in withdrawing the fibers from the mass. This appears to be the gist of the operation, viz, any fibers or linters, not sufficiently free from the mass will not detach themselves from the mass, but must move with the mass until adjoining fibers and linters have been

withdrawn to release the fibers that were previously secured to the mass and could not be released by the action of single teeth on the picker roll. The product is so well fleeced, that the suggested explanation seems plausible and correct. In other carding or Garnett devices the tendency is to securely hold a little mass of fibers by teeth on one roll and to pull fibers loose from the secured mass by engagement of numerous teeth on an adjoining roll. The difference seems to be that between forcefully pulling fibers from a mass, as practiced in old style machines, and working the mass by repeated engagement of single fibers of an unsecured mass, and directing centrifugal action upon the mass and fibers until the fibers gradually are loosened and are released from the mass and may then be carried away from the hopper by the teeth of the picker roll.

What is claimed is:

1. In a device for separating fibers from a mass of fibrous material, the combination of a hopper comprising walls, a pair of which extend downwardly and are spaced at their lower ends for providing a discharge opening between them, a picker roll adjacent the lower end of one of said pair of walls, an agitator roll adjacent the lower end of the other of said pair of walls, both of the rolls being located at said opening and cooperating with the walls for precluding discharge of material between either of said walls and its said adjacent roll, the rolls being so disposed adjacent one another, that they jointly support the mass within the hopper, and means for rotating each of the rolls in such direction and at such rate as to cause rapid rotation of the mass above the picker roll, to cause the picker roll to pick or separate loose fibers from the mass and to feed them between the rolls, to dash the mass against the hopper walls and to throw the separated fibers that have passed between the rolls, outwardly from said picker roll.

2. In a device for separating fibers from a mass of fibrous material, the combination of a hopper comprising walls, a pair of which extend downwardly and are spaced at their lower ends for providing a discharge opening between them, a picker roll adjacent the lower end of one of said pair of walls, an agitator roll adjacent the lower end of the other of said pair of walls, both of the rolls being located at said opening and cooperating with the walls for precluding discharge of material between either of said walls and its respective adjacent roll, the rolls being so disposed adjacent one another, that they jointly support the mass within the hopper, and means for rotating each of the rolls in such direction and at such rate as to cause breaking up of any lumps, loosening up the mass, keeping

the mass in loose moving condition and causing the picker roll to pick or separate loose fibers from the mass and to feed them between the rolls.

3. In a device for separating fibers from a mass of fibrous material, the combination of a hopper having a discharge opening in its walls, a picker roll adjacent an end of said hopper walls, an agitator roll adjacent another end of the hopper walls, both of the rolls being located at said opening and cooperating with the walls for precluding discharge of material between either of said wall ends and its respective adjacent roll, the rolls being so disposed adjacent one another, that they jointly support the mass within the hopper, and means for rotating each of the rolls in such direction and at such rate as to cause breaking and loosening of the mass and keeping the mass in loose moving condition above the picker roll, to cause the picker roll to pick or separate loose fibers from the mass and to feed them between the rolls.

4. In a device for separating fibers from a mass of fibrous material, the combination of a hopper comprising walls, a pair of which extend downwardly and are spaced at their lower ends for providing a discharge opening between them, a picker roll adjacent the lower end of one of said pair of walls, an agitator roll adjacent the lower end of the other of said pair of walls, both of the rolls being located at said opening and cooperating with the walls for precluding discharge of material between either of said walls and its respective adjacent roll, the rolls being so disposed adjacent one another, that they jointly support the mass within the hopper, and means for rotating each of the rolls in such direction and at such rate as to cause rapid rotation of the mass above the picker roll, to cause the picker roll to pick or separate loose fibers from the mass and to feed them between the rolls, and to throw the separated fibers that have passed between the rolls, outwardly from said picker roll.

5. In a device for separating fibers from a mass of fibrous material, the combination of a hopper comprising a pair of walls and having a discharge opening between the ends of said pair of walls, a picker roll adjacent one end of one of said pair of walls, said wall extending in substantial alignment with a diameter of the picker roll, an agitator roll adjacent the end of the second of the pair of walls, said second wall extending in substantial alignment with a diameter of the agitator roll, both the rolls being located at said discharge opening and cooperating with the walls for precluding discharge of material between each of said walls and its respective adjacent roll, the rolls being so disposed adjacent one another

that they jointly support the mass within the hopper, and means for rotating each of the rolls in such direction and at such rate as to cause rotation and breaking up of the mass above the picker roll, to cause the picker roll to pick or separate loose fibers from the mass, to feed them between the rolls, and to throw the separated fibers that have passed between the rolls, outwardly from said picker roll.

6. In a device for separating fibers from a mass of fibrous material, the combination of a hopper, comprising walls, a pair of which walls extend downwardly and have their lower ends spaced for providing a discharge opening between them and which walls, if continued, would meet at an acute angle, a picker roll and an agitator roll both located at said discharge opening and substantially one-half of each of said rolls being enclosed within the included angle formed at the apex of said pair of walls, and means for rotating each of the rolls in such direction and at such rate of speed as to cause breaking up of the mass above the picker roll, to cause the picker roll to pick or separate loose fibers from the mass, to feed the separated fibers between the rolls and to throw the separated fibers, that have passed between the rolls, outwardly from said picker roll.

7. In a device for separating fibers from a mass of fibrous material, the combination of a hopper comprising imperforate walls, a pair of which imperforate walls extend downwardly and have their lower ends spaced for providing a discharge opening between them and which walls, if continued, would meet at an acute angle, a picker roll and an agitator roll both located at said discharge opening and substantially one-half of each of said rolls being enclosed within the included angle formed at the apex of said pair of walls, and means for rotating each of the rolls in such direction and at such rate of speed as to cause rotation, breaking up and loosening up of the mass above the picker roll, to cause the picker roll to pick or separate loose fibers from the mass, to feed the separated fibers between the rolls and to throw the separated fibers, that have passed between the rolls, outwardly from said picker roll.

8. In a device for separating fibers from a mass of fibrous material, the combination of a hopper comprising walls having their lower ends spaced for providing a discharge opening, a toothed picker roll and a toothed agitator roll located at said discharge opening, the teeth of said rolls being pointed, one each of the rolls cooperating with the lower end of a different one of the hopper walls for precluding discharge of material between such walls and said rolls, the rolls being so disposed adjacent one another,

that they jointly support the mass within the hopper and the points of the teeth on one of the rolls projecting forwardly and the points of the teeth of the other roll projecting rearwardly and so related that loose fibers may pass between the teeth, and means for rotating each of the rolls in the same direction whereby adjacent portions of the rolls move in opposite directions, and at such rate as to cause rapid rotation of the mass above the picker roll, to cause the picker roll to pick or separate loose fibers from the mass, to feed them between the teeth of the rolls and to throw the separated fibers that have passed between the rolls, outwardly from said picker roll.

9. In a device for separating fibers from a mass of fibrous material, the combination of a hopper comprising walls, a pair of which walls converge upon one another and are spaced at their closest portions for providing a discharge opening between them, a picker roll adjacent one of said pair of walls, an agitator roll adjacent the other of said pair of walls, the rolls being both located at said opening and cooperating with the walls for precluding discharge of material between either of said walls and its respective adjacent roll, the rolls being so disposed adjacent one another that they jointly support the mass within the hopper, and means for rotating each of the rolls in such direction and at such rate as to cause rapid rotation of the mass above the picker roll, to cause the picker roll to pick or separate loose fibers from the mass and to feed the loose fibers between the rolls, to dash the mass against the converging walls and to throw the separated fibers, that have passed between the rolls, outwardly from said picker roll.

10. In a felting machine, the combination with a main cylinder and means cooperating therewith for felting fibrous material delivered to the cylinder, of means for preparing and delivering fibrous material to the cylinder and comprising a hopper having walls, a pair of which walls converge upon one another and are spaced at their closest portions for providing a discharge opening between them, a picker roll adjacent one of said pair of walls and spaced from the cylinder so that the cylinder can not remove fibers from the picker roll, an agitator roll adjacent the other of said pair of walls, the rolls being both located at said opening and cooperating with the walls for precluding discharge of material between either of said walls and its respective adjacent roll, the rolls being so disposed adjacent one another that they jointly support the mass within the hopper, and means for rotating each of the rolls in such direction and at such rate as to cause rapid rotation of the mass above the picker roll, to

cause the picker roll to pick or separate loose fibers from the mass and to feed them between the rolls, to dash the mass against the converging walls and to detach and throw the separated fibers, that have passed between the rolls, outwardly from said picker roll and onto the cylinder.

11. In a felting machine the combination of a hopper for material to be felted, comprising a pair of downwardly converging walls, spaced at their lower ends for providing a discharge opening, a toothed roll and an agitator roll in said opening, the one of said pair of converging walls terminating adjacent the toothed roll and cooperating therewith for precluding discharge of material between said roll and said wall, the second of said pair of converging walls terminating adjacent the agitator roll and cooperating therewith for precluding discharge of material between said agitator roll and said second of the pair of converging walls, the rolls being so disposed adjacent one another, that they jointly support the mass within the hopper, means for rotating each of the rolls in such direction and at such rate as to cause rapid rotation of the mass above the toothed roll, to cause the toothed roll to pick or separate loose fibers from the mass and to feed them between the rolls, and felting means for operation on the fibers fed between the rolls.

12. In a felting machine the combination of a hopper for material to be felted, comprising a pair of downwardly extending walls spaced at their lower ends for providing a discharge opening, a toothed roll and an agitator roll in said opening, the one of said pair of walls terminating adjacent the toothed roll and cooperating therewith for precluding discharge of material between said roll and said wall, the second of said pair of walls terminating adjacent the agitator roll and cooperating therewith for precluding discharge of the material between said agitator roll and the said second of said pair of walls, the rolls being so disposed adjacent one another that they jointly support the mass within the hopper, means for rotating each of the rolls in such direction and at such rate as to cause breaking up and loosening of the mass, to cause the toothed roll to pick or separate loose fibers from the mass and to feed them between the rolls, and felting means for operation on the fibers fed between the rolls.

In testimony whereof, I have hereunto subscribed my name this 16th day of May, 1927.
